DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

STEAM-BOILER ECONOMIZER PLANT.

1,289,182.

Specification of Letters Patent. Patented Dec. 31, 1918.

Application filed December 8, 1914. Serial No. 876,011.

To all whom it may concern:

Be it known that I, DAVID S. JACOBUS, a citizen of the United States, residing in Jersey City, in the county of Hudson and 5 State of New Jersey, have invented certain new and useful Improvements in Steam-Boiler Economizer Plants, of which the following is a specification.

In my application Serial No. 784,315, filed 10 August 12, 1913 liability of corrosion of an economizer is prevented or minimized by first heating the feed water, then withdrawing it from the heating apparatus and permitting the greater part of the air or gases 15 to escape before this water is fed to the economizer or a part thereof. In that application the feed water is heated by passing it through the low pressure stage of a plural stage economizer and then delivered to 20 a tank in which the greater part of the air or gases is permitted to escape. From this tank the water is forced through the high pressure stage of the economizer against the boiler pressure, the high pressure stage being 25 subjected to the hottest gases. To meet the requirements of modern power plant practice of large size boiler units and high overloads, I have used a wrought iron or wrought steel construction for the high pressure 30 sure stage of the economizer, being enabled to do so because of the practical elimination of the air and gases from the water before it is delivered to the high pressure stage. My invention also enables me to use 35 cast iron for the low pressure stage of the economizer, and thereby obtain the advantage of the less liability of cast iron, over wrought iron or steel, to corrosion.

The present invention relates to a special 40 arrangement of an economizer, and to a special form and arrangement of a two stage economizer. The entire economizer, or at least the high pressure part of a two stage economizer, is arranged for a down pass of 45 the gases over the economizer tubes and an upward pass of the feed water through the tubes. This prevents laning of the gases as well as of the feed water. This down pass of the gases also allows a long economizer 50 to be used with a single straight pass for the gases, thereby minimizing the frictional resistance of the gases. The invention will be understood by reference to the accompanying drawings in which Figure 1 is a more or less diagrammatic view, partly in vertical

section and partly in elevation, of a plant embodying the invention; Fig. 2 a rear view of the high pressure stage of the economizer of Fig. 1; Fig. 3 a detail showing the vent connection between the boxes of Fig. 2; Fig. 60 4 a diagrammatic view to illustrate the use of a common air releasing tank for two or more boilers; and Fig. 5 a diagrammatic view to illustrate the use of two or more boilers with high pressure economizer stages in connection with a single low pressure stage. Similar reference numerals indicate 65 similar parts in the several views.

Referring to Figs. 1, 2 and 3, the numeral 70 1 designates a portion of a boiler of any usual or standard design having a steam and water drum 2 to which the feed water is delivered from the high pressure stage of the economizer, said stage being designated generally by the letter "A." The rear of the latter is illustrated in Fig. 2, and in Fig. 1 said stage is shown as located in the vertical part of the flue 3, and as subjected to the hottest gases. The gases are made to travel in a downward direction 75 over the tubes of the high pressure stage, and the flow of the water through said stage is, in general, in the reverse direction of the flow of the gases. The low pressure stage 80 of the economizer, designated generally by the letter "B," is arranged in separated banks of vertical tubes in the horizontal part of the flue 3, and is subjected to the coldest gases. The gases finally enter a fan 4 and are delivered to the uptake 5. The fan 85 maintains the necessary draft suction. By setting the economizer partly above and partly below the boiler floor 6, improved results are secured as to head room and in 90 locating the induced draft apparatus in the basement instead of at a high level above the boiler. The feed water which may come from the hot well, or any other source, enters the pipe 7 through a valve 7', and is delivered to the low pressure stage of the 95 economizer, shown as consisting of three banks, 8, 9 and 10, each having five rows of tubes, preferably of cast iron, fitted into cast iron horizontal boxes or headers to form 100 transverse sections. It is to be understood, of course, that the invention is not limited to the exact number of tubes in a section or the exact number of sections shown. The spaces between the banks of tubes provide 105 for access to the low pressure stage of the 110

economizer through doors 11. Beneath each of these banks is a pit, having access doors 12, for collecting soot deposited from the gases, and that removed from the exterior 5 of the tubes by scrapers 13 hung by chains over wheels 14. The latter are geared to a shaft 15 adapted to be rotated in both directions to raise and lower the scrapers along the tubes. To secure an increase in economy 10 and efficiency the temperature of the water fed to the low pressure stage of the economizer should be such that fumes and moisture in the gases will be condensed on the tubes, and when such condition exists it is 15 highly important that there be ready access to the tubes, so that their surfaces may be reached by hand for removing any material which may become cemented on the outside of the tubes. It is also important to 20 obtain access for coating the tubes with paint, or other material, to prevent or minimize external corrosion. Even where scrapers are used the low pressure stage should be arranged for access, as a pasty material 25 may cling to the lower ends of the tubes and above the lower headers, and by providing access between the banks, and making the banks of a proper width, this material may be removed by hand when the 30 boiler is shut down. Should any of the fumes or vapor condensed from the gases run down the tubes to the lowermost headers, it will fall into the pit below the 35 economizer sections, which space is utilized for collecting the dust and soot scraped from the tubes.

The tubes of the several banks of the low pressure stage are so connected that the water entering through pipe 7 is distributed 40 through the lower connected headers of bank 8, and flows upward through all of the tubes of said bank to the upper headers thereof, and passes therefrom to the header of the right hand section or row of 45 tubes of bank 9, then down said row of tubes, and is distributed through the remaining four connected lower headers of bank 9, then upward through the four rows of tubes of 9, to the upper headers of said 50 bank, and downward through tubes 9' to the lower headers of bank 10 and then upward through all of the rows of tubes of bank 10 through pipe 16 to a tank 17, in which tank are preferably perforated plates 55 over which the water is made to flow, and by which it is broken up, to facilitate the disengagement and escape of the air and gases. The disengagement of the air and gases from the water is assisted by the heating 60 of the water in the low pressure stage of the economizer, and by maintaining a partial vacuum in the tank 17 by the vacuum pump 18 connected to said tank by pipe 19. 17' is a relief valve for limiting the 65 pressure in the tank 17. The tank 17 is

provided with the blow-off connection 17² for the removal of any sediment deposited therein. From the tank 17 the water is conducted by the pipe 20, leading from a point above the bottom of the tank, to a feed pump 21 which forces it through pipe 22 to the bottom of the high pressure stage of the economizer. Steam for operating the pumps 18 and 21 is supplied from a pipe 23, and in the connection for pump 21 75 is a valve 23' controlled by a float 24, so as to maintain a substantially uniform level of the water in tank 17. This regulating device varies the amount of steam supplied through the branch connection from pipe 23 to pump 21, and in that way regulates the speed of the pump 21.

The high pressure stage of the economizer is shown as consisting of a series of rows of tubes 25 expanded into horizontal boxes or 85 headers 26, and as having a slight inclination upward in the direction of flow of the water. The tubes and boxes are preferably of wrought iron or wrought steel to withstand the high boiler pressure to which this 90 stage of the economizer is subjected. The inlet pipe 22, from pump 21, enters the lowermost of the headers 26, as shown in Fig. 2, and by said header is distributed to the tubes of the lowermost row. The water then 95 flows through the successive rows of tubes, from side to side, as indicated by the arrows, until it leaves through pipe 27 by which it is delivered to the steam and water drum 2. The described flow of the water through the 100 high pressure stage of the economizer provides for a positive circulation, and the passage through tubes all of which are inclined 105 upward with reference to the direction of flow of the water. This causes any air or non-condensable gases which may not have been removed from the water in the tank 17 to be carried along with the general current and out of the economizer. It also allows of a construction which can be readily relieved of air on being filled with water from an empty state. The positive circulation 110 of water through the high pressure stage is also of great advantage in causing a maximum amount of heat absorption from 115 the gases.

The horizontal boxes or headers 26 of each row are spaced apart so that the tubes may be replaced by passing them between two of the boxes and into the hole in the box on the opposite side of the economizer. The tube is slipped in some distance through the box on the opposite side, then brought opposite the hole in the other box to which it is to be connected, and then drawn back to 120 the proper position. Another advantage of the construction is that the hand-hole fittings opposite to the tube ends for use in expanding the tubes may be made smaller than where the tubes are passed through 125 130

the hand-hole fittings, thus making it possible to construct a stronger box from the same thickness of material. Again, a single hand-hole fitting may be employed 5 for expanding two or more of the tubes, the expander being introduced through such hand-hole fitting. Where the hand-hole fittings do not admit the use of an expander with a straight shank, a jointed expander 10 may be employed. Another way of expanding the tubes is to use a jointed expander passed through hand-hole fittings in the ends of the boxes, in which case only as many hand-hole fittings need be provided in the 15 sides of the boxes as are desired for assisting in the manipulation of the jointed expander and for inspecting the tube ends. Replacing the tubes in the way described is advantageous also in making it possible to 20 set the boilers and economizers nearer together, that is, with less aisle room, than where the tubes are replaced through the hand-hole fittings. Should the tubes be replaced through the ordinary form of hand- 25 hole fittings, the aisle width would have to be such that the full length of a tube could be introduced at right-angles to the boxes, whereas with the arrangement described the tubes may be moved sidewise between the 30 boxes and introduced at an angle.

Still another advantage of this arrangement relates to cleaning the tubes. Owing to the boxes being spaced apart from each other in the rows and a space being left in 35 the separating bricks or material which may be used between the boxes, a steam or air lance may be inserted between the boxes either through special openings or through the doors 27 shown on Fig. 2. Such steam 40 or air lance will serve to blow off the soot and collection on the economizer tubes.

In Fig. 3 I have shown, on an enlarged scale, the manner of connecting the boxes 26 to prevent the pocketing of air in the upper 45 part of the boxes and to permit its escape to the uppermost box. As there shown, the connection consists of a relatively small pipe 26' extending from the top of one box to near the top of the box directly above it. 50 As so arranged the air or gases must flow all the way along each one of the boxes before it can enter the one directly above it; thus preventing short circuiting of the water without the removal of the air and causing 55 the air from the lowermost boxes to sweep through the full length of all of the upper boxes, which leads to the removal of any air bubbles which might otherwise lodge at certain points in the upper sides of the boxes. 60 In Fig. 3 I have also indicated hand-hole fittings 26² in the sides of the boxes for expanding the tube ends to make a tight joint. Each hand-hole fitting serves for the expansion of three tube ends, a jointed expander 65 being used. I have also shown hand-hole fit-

tings 26³ in the ends of the boxes through which a jointed expander may be introduced for expanding the tubes.

The high pressure stage of the economizer is especially applicable to conditions where 70 steam may be generated in the economizer. This feature will be useful in connection with waste heat work where the ratio of the work done in the economizer and the boiler varies a considerably greater amount than 75 in coal fired boiler furnaces. In a waste heat boiler the initial temperature of the gases may for a time be over 2000° F. The temperature of the gases may then fall to, say, approximately 1000° F., with the same, or 80 even a greater, weight of gas flowing through the boiler per hour as existed with the higher temperature. When a large volume of gas flows through the boiler and economizer at a low temperature, the relative amount of work done by the economizer, in proportion to that done by the boiler, is such that, if the economizer is designed to give the best results with the high temperature gases, steam will be formed in the 90 economizer with the low temperature gases. With the arrangement shown of the high pressure stage of the economizer, any steam formed therein will not have a tendency to carry over slugs of water as would be the 95 tendency in some other forms of economizers, such for example, as the form shown in the low pressure stage B. Should steam be formed in the middle bank of tubes in an economizer of the form used for the low 100 pressure stage it would be trapped in this bank, and to obtain an outlet would force the water downward through the tubes 9' leading from the top of the middle bank 9 to the bottom of the third bank 10. The 105 steam would then have to force its way through the water in the tubes of bank 10, and, in doing so, would be apt to carry over slugs of water.

In Fig. 4 I have shown, diagrammatically, 110 a plant in which the water from the low pressure stages of a plurality of boilers is run to a common tank 17. The feed water enters the low pressure stages of the economizers through pipes 7, and after passing 115 through the banks 8, 9 and 10 flows through branch pipes 16' to a common pipe 16 by which it is delivered to tank 17. The pipes 16' are provided with valves 16², and thermometers 16³. From tank 17 the water enters pipe 20 and is fed by the pump 21, through the pipe 22, into the high pressure stages of the economizers, entering these stages through the branch pipes 22' and leaving through the pipes 27, passing 120 through the feed valves in said pipes into the steam and water drums of the respective boilers. The amount of water fed to each high pressure stage may be regulated by adjusting the valves in the pipes 22'. The 130

amount of water fed to the low pressure stages may be estimated by noting the exit temperatures indicated by the thermometers 16². The pipes 16 and 22 are shown as open-ended to indicate that more than two boilers and economizers may be connected to the plant. The dry vacuum pump is shown at 18, the air and non-condensable gases withdrawn from tank 17 being discharged from 10 the pump through pipe 18'.

In Fig. 5 I have shown, diagrammatically, a plant in which is employed a single low pressure stage of a two-stage economizer in connection with two or more boilers each 15 having a high pressure stage. The water enters through pipe 7, and flowing through the banks 8, 9 and 10 of the low pressure stage B passes by the pipe 16', having a valve 16², into pipe 16 and tank 17. From 20 the latter the water is delivered through pipe 20 to pump 21 and by the latter is forced to the several high pressure stages, entering the same from pipe 22 through the branch connections 22', the amount of water 25 being regulated by means of the valves in the pipes 22'. From the high pressure stages the water enters the steam and water drums of the respective boilers through valves in the pipes 27. The amount of water 30 fed to the low pressure stage may be estimated by noting the exit temperature indicated by the thermometer 16³ in connection with the temperature of the water supplied to the low pressure stage.

35 The gases leaving the high pressure stages of the economizers pass through the lower dampers 28 and enter the common flue 29 from whence they either pass to the low pressure stage of the economizer through the dampers 30, or are by-passed around the economizer through the connection 31. When the low pressure stage of the economizer is in action the dampers 30 are open and the damper 32 is closed. When the 40 economizer is out of action, and the flue gases are by-passed, the damper 32 is opened and the dampers 30 and 33 are closed. The gases finally enter the fan 4 from whence they are forced into the uptake 5. A by-pass 45 connection may be provided for conveying the gases from the flue 31 directly to the stack when so desired without passing them through the fan.

50 As in Fig. 4 the pipes 16 and 22 are shown as open-ended to indicate that other units may be connected to the plant. The common flue 29 is also shown as open-ended to indicate that it may serve more than the two boilers shown.

60 The economizer may be of a one stage form in which case the vertical arrangement which has been described for the high pressure stage will give the advantages already described for such arrangement.

65 As has been stated, the drawings are dia-

grammatic. Certain common and well-known features such, for example, as safety valves for the economizers, have not been shown, in order to emphasize the features which apply more particularly to the invention.

70 What I claim and desire to secure by Letters Patent of the United States is:—

1. A steam boiler having an offtake flue with a vertically disposed portion and a 75 horizontally disposed portion, an economizer in said flue comprising a high pressure part or section in the vertically disposed portion thereof and having a series of horizontally extending tubes inclined upwardly to the 80 horizontal in the direction of the flow of the water, horizontal headers to which said tubes are connected, a low pressure part or section in the horizontally disposed portion of said flue and having a series of separated banks 85 of vertical tubes, and means for maintaining the water in said economizer sections under different pressures.

2. A steam boiler having an offtake flue with a vertically disposed portion and a 90 horizontally disposed portion, an economizer in said flue comprising a high pressure part or section in the vertically disposed portion thereof and having a series of horizontally extending tubes inclined upwardly to the 95 horizontal in the direction of the flow of the water, horizontal headers to which said tubes are connected, connections arranged to prevent pocketing of air in said headers, a low pressure part or section in the horizontally 100 disposed portion of said flue and having a series of separated banks of vertical tubes, and means for maintaining the water in said economizer sections under different pressures.

3. A steam boiler having an offtake flue with a vertically disposed portion and a horizontally disposed portion, an economizer in said flue comprising a high pressure part or section in the vertically disposed portion 110 thereof and having a series of horizontally extending tubes inclined upwardly to the horizontal in the direction of the flow of the water, horizontal headers to which said tubes are connected, a low pressure part or section in the horizontally disposed portion of said flue and having a series of separated banks 115 of vertical tubes, means intermediate the economizer sections arranged to allow air or gases to escape from the water heated in the low pressure part or section, and means for maintaining the water in said economizer sections under different pressures.

4. A steam boiler economizer comprising 125 a series of horizontal headers and horizontally extending tubes connecting the headers, said tubes being inclined from one header to the opposite header in the direction of the flow of the water and confining the flow of the water to a series of zig-zag 130

back and forth passes, means for admitting water to the lower set of tubes, and air connections on alternate ends from the upper part of one header to the upper part of the 5 header next above.

5. The herein-described system comprising a plurality of boilers each having a high pressure economizer part or section, a low pressure economizer part or section 10 common to all the boilers and feeding to the high pressure parts or sections, means for maintaining the water in said parts or sections under different pressures, and a by-pass to direct the gases either through or 15 around said low pressure part or section.

6. The herein-described system comprising a plurality of boilers each having a high pressure economizer part or section, a low

pressure economizer part or section common to all the boilers and feeding to the high 20 pressure parts or sections, means for maintaining the water in said parts or sections under different pressures, a by-pass to direct the gases either through or around said low pressure part or section, and means intermediate 25 the economizer sections arranged to allow air or gases to escape from the water heated in the cooler low pressure economizer part or section.

In testimony whereof I have hereunto 30 signed my name in the presence of two subscribing witnesses.

DAVID S. JACOBUS.
